Atty.

UNITED STATES PATENT OFFICE

2,465,583

WINDOW CONSTRUCTION

Jacob Fuchsman, Brooklyn, N. Y.

Application October 17, 1944, Serial No. 558,996

1 Claim. (Cl. 20—48)

1

This invention relates to window constructions and in particular to one wherein the windows may be opened inwardly and also vertically as desired, the inward swinging movement of the windows providing for easy cleaning of the panes thereof.

A particular object of the invention is to overcome the objections heretofore found in window-structures of the nature referred to, which were expensive to produce, had to be manufactured as part of the sash structure, and required considerable hardware to keep the window in condition for adjustment necessary in opening the sashes inwardly. A further objection was that windows pulled in had to be supported by one hand while cleaning of the pane was done with the other hand. To a woman this is inconvenient as the sash is usually heavy and the manipulation of the parts of the structure in order to remove the window frame from the sash frame or casement frame were a nuisance.

It is an object of my invention to mount within a pane holding frame as now commonly employed, an inner pane carrying frame so that the inner frame can be swung in for cleaning the glass and can be quickly and easily opened and closed and needs no support by the person cleaning the window. A still further object of the invention is the provision of a structure that can be applied to windows in use without altering the frame structure or cutting parts thereof away. A still further object of the invention is to provide a reinforce frame for the sash frame that will permit the use of an inner pane holding frame without allowing the sash frame to warp, become distorted or misshaped. A further object is to provide a complete window sash or pane holding frame which can be quickly and easily put into any sliding sash frame by the removal of the parting strips and without altering the rest of the window construction.

With these and other objects in view, the window invention comprises certain constructions hereinafter described and then particularly pointed out in the claim and a preferred embodiment of my invention is illustrated in the accompanying drawing, in which;

Figure 1 is a view in elevation of a window constructed in accordance with my invention, the sash frame being included in part,

Figure 2 is a view in sectional elevation taken through the window structure shown in Figure 1 and illustrating the relative position of the sashes when the window is closed normally,

Figure 3 is a fragmentary section similar to 55 extend across the upper part of the upper sash

2

Figure 2, but showing only a portion thereof and illustrating the relation between the sashes when the lower one is raised to permit the window frame of the upper sash, which is in lower position, to be opened without interference, and

Figure 4 is a view in perspective of a reinforce frame employed in connection with the lower sash frame to permit the use of a relatively thin wood structure in which is hinged the window pane carrying frame.

Referring to the drawing in detail, 10 indicates a portion of the well known casement or box frame which is set into the window opening of a building for the purpose of holding the upper sash frame 11 and the lower sash frame 12, which, as is well known, are supported for balanced sliding movement in said sash frame holding casement, and separated from each other by the parting strips 13 and 14, which define the grooves in which said sash frames operate.

In the use of my invention, I contemplate the mounting of upper and lower window pane carrying frames 15, 15a respectively which I may refer to as glass frames, within the confines of the sash frame and to do so without altering the inner glass size or dimension or the outer dimensions of the sash frame from the standards now employed so that the sashes may be made up and sold separately for insertion into existing window structures without alteration to the latter. The sash frames in present use are too weak to permit the use of an inner separate frame for carrying the glass panes and I make use of metal reinforce frames 16, 16a for use with both upper and lower sashes 11 and 12 respectively. While the reinforce frames are not exactly alike they vary only in the details necessary to fit them to their associated sashes and for this reason I deem it necessary to illustrate only the lower frame 16a, which as illustrated in Figure 4 consists of a single sheet of metal or other suitable material of substantial rigidity that will resist any warping or distortion of the sash frame in connection with which it is used.

The reinforce frame 16a consists of upper and lower portions or end walls 17 and 18 respectively which embrace the upper and lower edges of the sash frame, side flanges or walls 19 and 20 for holding the side edges of the sash frame securely, and an outer edge flange 21 extending all around and abutting the outer face of the sash with which it is associated. The upper or lower sash frame reinforce members may be provided with front or inner flanges 22, 22a respectively, which

frame and the lower part of the lower sash frame. The depth of the horizontal portions 24, 24a of the sash frames is less than normally employed, and the part of the outer edge flanges 21 that project beyond the portions 24 act as retainers to prevent the outward opening of the inner pane frames or glass frames 15, 15a which are hinged as at 25, 25a respectively to the vertical edges of the sash frames 11 and 12. This is also true of the vertical flanged edges 26, 26a of the reinforce frames which extend beyond the vertical members 27, 27b of the sashes 11 and 12 respectively and act as a stop for the closing movement of said glass frames. Further reinforce action is provided by the depending tabs 27a and at the side edges of the sash frames, these reinforce frames are so shaped that they allow for the insertion and operation of the sash cords.

In order to render the window constructions waterproof, I provide strips 29, 29a along the lower parts 28, 28a of the glass frames 15, 15a respectively which serve to hold the lower edges of the glass panes 30, 30a in place and overlie the upper edge of the flanged portions 21, 21a of the reinforce frames. The reinforce frame used on the lower sash may be flared outwardly as at 31 in its upper portion to seal the meeting edges of the upper and lower sash frames, in which event, use is made of a filler piece 32 between the reinforce frame and the top parts of both the sash and glass frames. The strip 32 is supported along its lower edge by the turned over portion 33 of the upper flange of the reinforce frame, which serve as a stop to limit the swinging action of the glass frame.

In order to maintain the glass frames closed and securely in position within the sash frames, I employ catches 35, 35a pivoted in said glass frames, as shown in Figure 1. When the upper and lower sash frames 11 and 12 are in the normal window closing position as shown in the sectional view of Figure 2, it will be evident that the upper glass frame 15 cannot be opened because of the position of the upper part of the lower sash and it is necessary to lower the upper sash until it touches the casement frame and at this position as shown in Figure 3, the upper glass frame will clear the lower raised sash frame and the former can be opened inwardly about its hinges, the glass frame being in partly open position in said figure.

It is quite evident that with my improved structure, old sash frames can be removed and my new ones installed without altering the construction of the casement frames and with new window installments they may be sold as part of the entire window assembly. They provide an easy

and convenient manner in which the glass of the window may be cleaned without the necessity of getting outside the window, thus eliminating a danger in cleaning windows from the outside.

The frame 16a shown in Figure 4 is the one that embraces the lower sash frame 12, but when it is inverted in position, it substantially illustrates the frame that embraces the upper sash 11.

My invention is not to be restricted to the precise details of construction shown since various changes and modifications may be made therein without departing from the scope of the invention or sacrificing the advantages derived from its use.

What I claim is:

In a window structure, the combination with each of upper and lower sliding sash frames, of substantially like rigid metal reinforce frames each shaped to provide an integral flat flange portion of rectangular frame shape, the ends and sides of said portion being bent at right angles to provide end and side walls respectively, an end wall being bent to provide a front vertical flange coacting with the adjacent flat flange portion and the end wall formed therefrom to form a channel into which one end of a sash frame closely fits, the side edges and top of said sash frame being embraced by said end and side walls of the reinforce frame, said end and side walls being cut out to provide passages for sash frame supporting means, a glass frame hinged in said sash frame and the upper and lower edges of said flat flange portion extending beyond the upper and lower inner edges of said sash frame and constituting a stop for limiting the pivotal swing of the glass frame in closing movement and the channel portions of the reversed reinforce frames being horizontally aligned when the sashes are closed to prevent opening of the glass frame of the upper sash frame.

JACOB FUCHSMAN.
